UNITED STATES PATENT OFFICE.

GEORGE F. BEAN, OF NEW HAVEN, CONNECTICUT, ASSIGNOR OF ONE-HALF TO HOWARD E. WHITING, OF NEW HAVEN, CONNECTICUT.

LATHE-CHUCK.

No. 796,177.

Specification of Letters Patent.

Patented Aug. 1, 1905.

Application filed October 24, 1904. Serial No. 229,692.

To all whom it may concern:

Be it known that I, GEORGE F. BEAN, a citizen of the United States, residing at New Haven, in the county of New Haven and State of Connecticut, have invented a new and useful Improvement in Lathe-Chucks; and I do hereby declare the following, when taken in connection with the accompanying drawings and the numerals of reference marked thereon, to be a full, clear, and exact description of the same, and which said drawings constitute part of this specification, and represent, in—

Figure 1 a view, partly in side elevation and partly in section, of a chuck constructed in accordance with my invention; Fig. 2, a broken view, in inside elevation, of a portion of the rear member of the chuck-body, showing the adjusting-plug employed for radially moving one of the jaw-adjusting screws from which the jaw has been detached; Fig. 3, a detached broken view of the outer end of one of the jaw-adjusting screws, a portion of which is broken away to show its spline or key; Fig. 4, a detached plan view of one of the bevel-pinions; Fig. 5, a detached plan view of one of the adjusting-plugs; Fig. 6, a sectional view thereof; Fig. 7, a detached plan view of one of the coupling-nuts; Fig. 8, a sectional view thereof.

My invention relates to an improvement in universal lathe-chucks, the object being to produce a simple, compact, durable, and effective chuck constructed with particular reference to having its jaws independently adjusted in case they get out of truth.

With these ends in view my invention consists in a lathe-chuck having certain details of construction and combinations of parts, as will be hereinafter described, and particularly recited in the claims.

In carrying out my invention I form the jaw-adjusting screw 2 of each of the chuck-jaws 3 with a spline or key 4, entering a corresponding groove 5, leading out of the central hole 6, formed in the beveled pinion 7 for the passage through the same of the screw. Under this construction the screw and pinion are coupled together, so that the pinion will turn with the screw in either direction without, however, interfering with the radial movement of the screw with respect to the pinion within the limits of the length of the spline 4, which should be made long enough to cover the utmost adjustment that will ever

be called upon to bring the jaws into truth. Each screw 2 is also provided with a coupling-flange 8, located near the outer end of the feather 4 and adapted to be entered into a recess 9 in the inner face of a peripherally-threaded disk-shaped adjusting-plug 10, the outer face of which is also formed with a recess 11 for the reception of a coupling-nut 12, applied to screw-threads 13, formed at the base of the squared outer end 14 of the screw 2, to which, as shown, the nut 12 is locked by means of a pin 15. The adjusting-plug 10 is located in a threaded plug-recess 16, formed in the periphery of the chuck-body, which comprises, as usual, an outer part 17 and an inner part 18. A set-screw 19, mounted in the part 18 of the chuck-body, coacts with a threaded block 20 in locking the plug 10 against rotation. The outer face of the plug 10 is formed with radial grooves 21 for the reception of a spanner-wrench whereby the plug is turned in one direction or the other. The pinions 7 are located in suitable pinion recesses or chambers 22 in the chuck-body and all mesh into an annular universal rack 23, housed within the rear part 18 of the chuck-body in the usual manner, the outer and inner walls of the said recesses holding the pinions against radial movement outward or inward. The said pinion-recesses 22 are located in line with the plug-recesses 16, the former being located within the latter, as clearly shown. The inner ends of all of the adjusting-screws 2 are threaded, as usual, for passing through the inner ends of the jaws 3.

It will be understood from the foregoing that when any one of the screws 2 is turned by the application of a wrench or key to its squared outer end 14 it will turn its pinion, which will move the annular rack so as to correspondingly turn the other pinions and correspondingly move the other jaws. This is the universal feature of the chuck. When any one jaw is moved, all of the other jaws are moved to the same extent. Now suppose one of the jaws is not true with relation to one or more of its fellows. The set-screw 19 of the particular jaw to be trued up will be unscrewed, so as to release the adjusting-plug 10 of the jaw in question. A spanner-wrench is now applied to the adjusting-plug and the same turned inward or outward, as required, whereby the adjusting-screw 2 will be moved radially inward or outward, so as to corre-

spondingly move its jaw, without, however, disturbing its beveled pinion 7 or the beveled pinions 7 of the other jaws. Then after the jaw has been trued up the set-screw 19 is screwed in, so as to again bind the adjusting-plug 10.

It is apparent that in carrying out my invention some changes from the construction herein shown and described may be made. I would therefore have it understood that I do not limit myself thereto, but hold myself at liberty to make such departures therefrom as fairly fall within the spirit and scope of my invention.

Having fully described my invention, what I claim as new, and desire to secure by Letters Patent, is—

1. In a universal lathe-chuck, the combination with a chuck-body having pinion-recesses and plug-recesses located in line with each other, of radially-movable jaws, pinions for the respective jaws located in the said pinion-recesses in which they are held against radial movement outward or inward, a universal rack engaged by all of the pinions, adjusting-screws passing through the respective pinions with which they are coupled for rotation but through which they are radially movable, externally-threaded adjusting-plugs respectively located in the said plug-recesses, and means for coupling the outer ends of the

respective screws with the complementary adjusting-plugs, whereby by turning the said plugs, the said screws may be radially adjusted independently of each other.

2. In a universal lathe-chuck, the combination with a chuck-body having pinion-recesses and plug-recesses located in line with each other, of radially-movable jaws, pinions for the respective jaws located in the said pinion-recesses in which they are held against movement outward or inward, a universal rack engaged by all of the said pinions, adjusting-screws passing through the respective pinions with which they are coupled for rotation but through which they are radially movable, adjusting-plugs respectively located in the said plug-recesses and externally-threaded for taking into the threads thereof, fixed coupling-flanges located upon the screws and coacting with the inner faces of the said plugs, and coupling-washers removably mounted upon the screws and coacting with the outer faces of the said plugs.

In testimony whereof I have signed this specification in the presence of two subscribing witnesses.

GEORGE F. BEAN.
